UNITED STATES PATENT OFFICE.

SAMUEL TOY, OF BOSTON, MASSACHUSETTS.

TIME-CONTROLLED REMINDER APPARATUS.

1,416,910.

Specification of Letters Patent. Patented May 23, 1922.

Application filed March 16, 1921. Serial No. 452,712.

To all whom it may concern:

Be it known that I, SAMUEL TOY, a citizen of the United States, residing at Boston, in the county of Suffolk and State of Massachusetts, have invented certain new and useful Improvements in Time-Controlled Reminder Apparatus, of which the following is a specification.

My invention relates to time controlled reminder apparatus and it has for its object to provide an improved time controlled apparatus of this character which may be adjusted manually so as to operate automatically at a predetermined future time to call attention to memoranda requiring attention at that future time.

To this end my invention consists of a time controlled memoranda apparatus of the class described having the novel features 20 of construction and peculiar mode of operation set forth in the following description and particularly pointed out and defined in the claims at the close thereof.

In the accompanying drawings:

25 Figure 1 is a front elevation, partly broken away and in section, of a time controlled reminder apparatus constructed in accordance with my invention.

Figure 2 is a section on line 2—2 of Fig. 1.

30 Figure 3 is a section on line 3—3 of Fig. 2.

Figure 4 is a detail in perspective of one of the solenoids hereinafter referred to.

Figures 5 and 6 are details relating to the 35 clock mechanism hereinafter referred to.

Figure 7 is a diagram illustrating the wiring of the apparatus shown in Figs. 1 and 2.

The embodiment of my invention herein shown comprises a cabinet 1 whose front 40 wall 2 is made with a circular opening 3 within which is secured a pane of glass 4. The cabinet is provided upon its interior and near the lower end thereof with a horizontal partition 5 which, together with the bottom 45 wall 6, side walls 7 and 8, and back wall 9, provides a card holding compartment 10 within which is arranged a drawer 11. This drawer 11 is movable into and out of compartment 10 through a doorway 12 provided 50 in front wall 2 of the cabinet, said drawer being adapted to hold a supply of cards 13.

Within the cabinet 1, just back of the front wall 2 thereof, and parallel with the latter, is a vertical wall 14 made from wood or

other insulating material, upon the outer 55 face of which is a circular series of contacts 15 of which there are three hundred and sixty-six. Each contact 15 is made with a shank 16 extending through and fixed in the wall 14, said shank being adapted to 60 have an electric conductor wire fastened to its inner end. The circular series of contacts 15 is disposed concentrically about the axis of a shaft 17 carrying contact arm 18, which, by rotation of shaft 17, is caused to traverse 65 the circular series of contacts 15.

The shaft 17 is journaled in a bushing forming part of the frame 19 of a clock mechanism 20 and carries a gear 21 driven through a train of gears 22 by a spring 23 70 connected with a shaft 24, said shaft carrying the first gear of the train 22. A pendulum 25 pivotally supported at 26 is provided with a pallet 27 of usual construction co-operating with a pallet wheel 28 fast on the 75 shaft 29. This shaft 29 is connected through a train of gears 30 with a gear 31 loosely mounted on the shaft 24 and carrying a pawl 32 engaging a ratchet wheel 33 on shaft 24. The pendulum 25 and the mechanism through which it is connected with the shaft 24 constitutes the usual governor mechanism of the clock. The governor mechanism together with the train of gears 22 causes the spring 23 to rotate the shaft 85 17 and contact arm 18 once in every three hundred and sixty-six days, or, roughly speaking, once every year, and since there are three hundred and sixty-six of the contacts 15 it will be clear that the contact arm 18 90 will pass from one contact 15 to the next every twenty-four hours.

The shaft 24 of the clock mechanism is squared at its right hand end, Fig. 2, to receive upon it a key by means of which the 95 spring 23 is wound up, access to the clock mechanism for the purposes of adjustment or rewinding being had through a removable panel 34 forming part of the rear wall of the cabinet.

The cabinet 1 is constructed with a top wall 35 hinged at 36 to the rear wall 1 and provided at its front edge with a depending front wall section 2a consisting in part of a pane of glass 37 through which the upper 105 portion of the interior of the cabinet may be seen. By swinging the top wall 35 upwardly on its hinge 36 access may be had to

the upper portion of the cabinet. This upper portion of the cabinet is divided horizontally by a partition 38 between which and top wall 35 is a compartment 39 containing 5 three hundred and sixty-six card holders 40, each constructed with a pair of spring jaws 41, Figs. 2 and 4, adapted to grip a card between them and hold the same in an upright position. Each card holder 40 is 10 fastened to the upper end of a core member 42 comprising a metal middle section 43 which serves as the core for a solenoid winding 44. The lower end portion of each core member 42 extends through a horizontal partition 45 and is provided at its lower end with a head 46 adapted by its engagement with the under side of partition 45 to serve as a stop to limit the upward movement of the core of the solenoid.

15 20 The front portion of the cabinet 1 is constructed with a shelf 47 provided with twelve tapped holes in each of which is mounted a manually and vertically adjustable screw contact 48, co-operating at its inner end with 25 a separate fixed contact 49 within the cabinet. There are twelve of these contacts 49 fixed in position upon the inner side of the section 2^b of the front wall of the cabinet, one for each screw 48, and, as stated, there 30 are twelve screws 48, one for each month of the year.

35 The front wall section 2^b is disposed a short distance to the rear of the upper end of the front wall 2 so as to provide another shelf 50 constituted by the forward end of partition 38. This shelf 50 is provided with thirty-one tapped holes in each of which is mounted a manually operated screw contact 51 co-operating at its inner end with a fixed 40 spring contact 52 fixed to the under side of partition 38. There are, as stated, thirty-one adjustable screw contacts 51, one for each day of the month, and upon the outside of the frame of the cabinet adjacent 45 each of said contacts is a number corresponding with the number of the day of the month represented by that contact. Adjacent each screw contact 48, also, is the name of the month represented by that contact.

50 55 Within the cabinet and near the front thereof is an electrically operated bell 53 and a battery 54. The front wall 2 of the cabinet immediately in front of bell 53 is formed with apertures 55 so that the bell 55 may be clearly heard from the outside of the cabinet.

60 The operation of my improved apparatus is as follows: The user desiring to set the apparatus so that it will operate automatically to call his attention at a future date to memoranda, removes one of the cards from drawer 11 and writes the memoranda upon the same. There are three hundred and sixty-six card holders 40, one for each day 65 of a leap year, and each holder is inscribed

with the name of the day represented by it. Therefore, after writing the memoranda upon the card the user lifts the cover 35 and places the card within the holder 40 representing or corresponding to, the day upon 70 which he desires to have his attention attracted to the memoranda. He then manually turns down against its contact 49 the screw 48 of the month within which that day occurs and also screws down against its 75 contact 52 the screw 51 corresponding with the selected day of that month. Now, when the contact arm 18, during its movement over the series of contacts 15, passes on to contact 15 corresponding with the selected day for 80 which the apparatus has been adjusted, the circuit through the solenoid winding of the card holder 40 within which the card was placed is completed, thus energizing the solenoid and causing it to lift the solenoid 85 member 42 connected with said card holder, upwardly until its stop 46 engages the partition 45. At the same time the circuit is completed through the bell 53 which audibly signals the user and attracts his attention to the memoranda card which has been lifted as described. In Fig. 2 one of the core members 42 is shown in its uppermost position with the card held thereby lifted above the plane of the other cards and separately displayed. The contacts 15 and contact arm 18 are preferably so constructed that the latter dwells upon each contact 15 for a period of about eight hours. Of course upward movement of either screw 100 48 or 51 breaks the circuit through the solenoid energized as described and at the same time breaks the circuit through the bell 53.

I have herein provided means for audibly 105 signalling the fact that the spring 23 needs re-winding when such is the case, said means including a fixed contact 57 mounted on partition 5 in position to be engaged by the spring 23 when the latter is fully unwound. 110 The spring and contact 57 are arranged in a shunt circuit 58, Fig. 7, including the bell 53 so that it will be clear that when the spring becomes unwound it will engage contact 57 thereby closing this shunt and operating the bell.

115 The wiring of the apparatus, see Fig. 7, includes thirty-one conductors 59, each connected at one end with one of the thirty-one fixed contacts 52. The conductor 59 120 that is connected with the first contact 52, at the left in Figs. 1 and 7, is also connected by wires 60 with all twelve of the first day solenoids 44; the conductor 59 that is connected with the second contact 52 is also 125 connected by wires 60 with all twelve of the second day solenoids 44, and in like fashion throughout the series of contacts 52 the latter are connected each with the twelve or less solenoids 44 corresponding with the days of 130

the several months represented by the manually operated switch of which each of said contacts forms part.

At the start of a year the contact arm 18 occupies a vertical position above the shaft 17, and during the operation of the machine said arm travels in a clockwise direction over the series of day contacts 15, as well as over a concentric series of segmental month contacts 62. The twelve month contacts 62 are fixed to the outer face of wall 14 and as arm 18 rotates it acts as a bridge to successively connect the month and day contacts. The first month contact 62 is positioned and made of a length to be engaged by arm 18 while the latter is traversing the first thirty-one day contacts 15 which are allotted to the thirty one days of January; the second month contact 62 is in engagement with arm 18 while the latter is traversing the next twenty-nine day contacts 15 which are allotted to the month of February; the third month contact 62 is in engagement with the arm 18 while the latter is traversing the next thirty-one day contacts 15 which are allotted to the month of March, and so on throughout the series of month contacts 62.

The month contacts 62 are connected by wires 63, each with one of the fixed contacts 49, the January month contact 62 being connected with the contact 49 of the "Jan." switch 48-49; the February month contact 62 with the contact 49 of the "Feb." switch 48-49, and so on throughout the series of month contacts.

The tapped holes within which the twelve screws 48 are mounted are all formed in a single metal conductor strip 64 set into and forming part of the shelf 47, while the 40 tapped holes within which the thirty-one screws 51 are mounted are all formed in another single metal conductor strip 65 set into and forming part of the other shelf 50. The conductor strip 64 is connected by a wire 45 66 with one binding post of bell 53 whose other binding post is connected by a wire 67 with one pole of battery 54. The other pole of battery 54 is connected by a wire 68 with the other metal conductor strip 65.

50 The day contacts 15 are connected by wires 69, each with one of the solenoids 44, the first, second, third, etc., contacts of the group of day contacts 15 opposite each month contact 62 being thus connected in circuit with 55 the first, second, third, etc., solenoids, respectively, of the group of solenoids allotted to the month corresponding to said month contact. That is, the winding of each solenoid is connected by a wire 69 with the day contact 15 corresponding to the day and month inscribed upon the holder 40 of said solenoid.

60 From the diagram, Fig. 7, it will be clear that while arm 18 is upon any one of the 65 month contacts 62 whose month switch

48-49 has been closed, said month contact is electrically connected through wire 63; its closed month switch 48-49; wire 66; bell 53, and wire 67, with one pole of battery 54, and that if the arm 18 passes onto 70 a day contact 15 that is connected through its wire 69; solenoid 44; wire 60 and wire 59, with a day switch 51-52 that is closed, then a circuit will be completed by arm 18, acting as a bridge, through said solenoid 75 and the bell 53. This circuit is traced as follows: From one pole of battery 54 through wire 67, bell 53, wire 66, conductor strip 64, the closed switch 48-49, wire 63 leading from the latter, the month contact 80 62 with which said wire is connected, arm 18, the day contact 15 then engaged by said arm, the wire 69 connected with said day contact, the solenoid with which said wire is connected, the wire 60 of said solenoid, the 85 wire 59 to which said wire 60 is joined, the closed day switch 51-52, conductor bar 65 and wire 68 to the opposite pole of the battery.

Thus by closing the month switch 48-49 90 and day switch 51-52 corresponding with any one or more selected days of the year, the apparatus may be adjusted so that it will operate automatically upon those days to sound a signal and display the memorandum 95 cards placed in the holders corresponding with those days.

What I claim is:

1. An apparatus of the character described comprising a plurality of electrically operated memoranda displaying instruments; circuits in which said instruments are arranged; a set of manually adjusted month switches and a set of manually adjusted day switches by means of which sets of switches 100 said circuits are prepared for selective operation, and clock mechanism by which said circuits are selectively operated according to the adjustment of said switches.

2. An apparatus of the character described 110 comprising a plurality of electrically operated memoranda displaying instruments; circuits in which said instruments are arranged, and manually adjusted means including clock mechanism by which said circuits and instruments are selectively operated at predetermined times.

3. An apparatus of the character described 115 constructed in accordance with claim 2 and having also an audible signalling instrument 120 that is automatically operated each time one of the memoranda displaying instruments is operated.

4. An apparatus of the character described 125 comprising a plurality of electrically operated memoranda displaying instruments; circuits in which said instruments are arranged; an electrically operated audible signalling instrument in circuit with said memoranda displaying instruments, and man- 130

ually adjusted means including clock mechanism for selectively operating said circuits and displaying instruments at predetermined times and for operating said signalling instrument each time one of said displaying instruments is operated.

5. An apparatus of the character described comprising a cabinet made with a card holding compartment; a plurality of electrically operated memoranda displaying instruments mounted within said cabinet, each constructed with a movable card holding member normally occupying a retracted position; circuits in which said instruments are arranged; 10 an electrically operated signalling instrument within said cabinet and in circuit with said memoranda displaying instruments; a battery within said cabinet and in circuit with said displaying instruments and said 15 signalling instrument, and manually adjusted means including clock mechanism for selectively operating said circuits and said displaying instruments to project the card holding members thereof at predetermined times,

and for operating said signalling instrument 25 each time one of said displaying instruments is operated.

6. An apparatus of the character described comprising a plurality of electrically operated memoranda displaying instruments; a 30 battery; conductors for connecting each of said memoranda displaying instruments with one pole of the battery; a set of manually adjusted and normally open day switches each controlling one of said conductors; a 35 circular series or relatively short fixed day contacts; conductors for connecting each day contact with one of said displaying instruments; a circular series of relatively 40 long fixed month contacts; conductors for connecting each month contact with the opposite pole of said battery, and a second set of manually adjusted and normally open month switches each controlling one of said 45 last mentioned conductors.

In testimony whereof I have affixed my signature.

SAMUEL TOY.
